ELECTRICALLY OPERATED STERILIZER ASSEMBLY FOR TOOTHBRUSHES AND THE LIKE

Gordon L. Braund, Melbourne Beach, Fla., assignor, by direct and mesne assignments, to Mark VII Industries, Inc., Sarasota, Fla., a corporation of Florida

Continuation-in-part of design application Ser. No. 9,332, Nov. 8, 1967. This application Sept. 11, 1968, Ser. No. 13,502

Term of patent 14 years

Int. Cl. D24—03

U.S. Cl. D83—1

FIG. 1

FIG. 2

FIG. 4

FIG. 3

FIG. 5

FIGURE 1 is a front elevational view of my electrically operated sterilizer assembly for toothbrushes and the like, embodying my new design.

FIGURE 2 is a rear view of same.

FIGURE 3 is a side view of same with the opposite side having a like appearance.

FIGURE 4 is a top plan view.

FIGURE 5 is a bottom plan view.

This is a continuation-in-part of design application Ser. No. 9,332, filed Nov. 8, 1967 and now abandoned.

I claim:

The ornamental design for an electrically operated sterilizer assembly for toothbrushes and the like, substantially as shown and described.
